POCKET FASTENER FOR PENS
AND THE LIKE

Clarence F. Norlin, Chicago, Ill.

Application August 30, 1945, Serial No. 613,669

2 Claims. (Cl. 24—11)

1

This invention relates to pocket fastening means employed for pens, pencils, thermometers, instruments, screw drivers and the like, etc. In order to show one application of the invention herein described, the fastening means is shown as attached to a fountain pen from which it will be seen that other applications are analogously possible for many other purposes.

Heretofore, pen and pencil clips have proven unsatisfactory primarily for the reason that such clips are either too tight or too loose. In the former case, it eventually leads to the tearing of the wearer's pocket material as well as presenting the difficulty of slipping the clip over the edge of the pocket. In the case of the clips being too loose, there is always the possibility that the wearer may lose the pen or the same loosens and slides down into the pocket bottom to the inconvenience of the user.

It is one of the main objects of the present invention to provide pocket fastening means for pens or the like which provides a suitable clip that is carried by the pen for movement toward or away therefrom, and to provide means selectively movable and carried by the pen which cooperates with the clip to actuate the same toward the surface of the pen or away therefrom. In this manner, the clip may be moved outwardly away from the pen to permit easy insertion over the pocket material to bring the latter between the clip and the pen, and by moving the adjustable means, the clip is urged toward the pen surface to clamp the wearer's pocket material tightly in pen holding position between the clip and the pen. This establishes a convenient and easily operated clip structure that safeguards against the loss or displacement of the pen or the like as the case may be.

Another object of the present invention is to provide one or more of such clips which are also movable toward or away from the surface of the pen, these clips having hooks connected therewith for the purpose of partially or entirely penetrating the pocket material adjacent a clip to further safeguard the loss or displacement of the particular instrument to which such fastening means is attached.

There are other features and advantages associated with the present invention which shall hereinafter be expressed in the following detailed description having reference to the accompanying drawings forming a part of this specification.

In the drawings:

Fig. 1 is a fragmentary elevational view of a portion of a fountain pen having the fastening

2

means of the present invention attached thereto; and

Fig. 2 is another fragmentary portion of a fountain pen illustrating a modified arrangement of fastening means.

A preferred construction of pocket fastener is illustrated in Fig. 1 as applied to the cap end of a fountain pen. This construction comprises a pen 10 having a cap 11 formed with a reduced end 12 having a cap portion 13 providing a head and a shoulder 14. A resilient clip 15 is carried by the cap for movement toward and away from the side surface thereof and may be secured to the cap in any fashion to obtain this particular movement. With the present construction, the end 16 is secured to the head 12 as shown in Fig. 1, such clip having a horizontally disposed portion 17 recessed within the side slot 18 in the reduced portion 12 of the head, the slot 18 holding the clip 15 against lateral displacement relative to the side of the cap of the pen. The outer free end 19 of the clip is formed into a hook 20 shaped substantially as shown in Fig. 1.

Adjustable means in the form of a ring 21 encircles the reduced portion 12 of the cap and is outwardly knurled as shown to form a grip for selective finger operation whereby this ring may be moved into the dotted line position in Fig. 1 or into the full line position as there shown. The inner peripheral surface 22 of the ring acts to cam the horizontally disposed portion 17 of the clip into different selected positions within the recess 18. Two positions are shown in Fig. 1 wherein the clip 15 is positioned with the hook 20 against the side of the cap 11 and the other position is shown in dotted lines where the clip is moved outwardly by its resiliency into its extreme outward position when the adjustable ring 21 is moved against the shoulder 14 of the head 13.

Attention is directed to the fact that the clip 15 is of a semi-resilient or entirely resilient material and is formed for normal disposition in the dotted line location shown in Fig. 1. By moving the adjustable ring into the full line position shown in Fig. 1, the spring clip is moved toward the surface of the pen so as to penetrate the pocket material of a wearer and/or grip the cloth and clamp the same tightly against the surface of the pen thereby holding the pen in place and against loss thereof. Also, it should be noted that various shapes of clips may be employed and can be appropriately formed to obtain various coacting relationships between the clip and the pen body or the cap surface as demonstrated in this construction.

Referring to Fig. 2, a modified construction of pocket holding means for pens or the like includes a pivotally mounted operating means in the form of the ring 23 which can be moved into one of two positions determined by the depressions 24 and 25 in the spring clip 26. Clip 26 is secured to the cap in any suitable recess 30 which permits the depression of the notched end of the clip 26 under the action of the cam portion of the swingable loop 23. This loop or ring 23 is 10 pivotally supported at 31 from a suitable ear or ears 32 connected and formed as part of the tip 27. The portion of the ring 23 which engages the depressions or notches 24 and 25 of the clip 26 is shown at 33 and a knurled knob 34 is oppositely disposed from the cam portion 33 of the ring 23. It should also be noted that this knurled knob 34 15 is protected from brushing loose and moving into the notch 24 position by being substantially confined within the protected confines of the bend 35 in the clip 26.

The Fig. 2 construction also includes a hooked end 36 forming a portion of the clip 26, and this hooked end 36 may be adapted to fit into a suitable recess or opening 37 formed in the side of 25 the body of the pen cap 28 as shown.

Other variations and modifications in the exact form, combination of elements, and in the constructions shown and described are contemplated. Such variations and modifications shall be governed by the breadth and scope of the appended claims directed to the structures exemplifying the principles of the present invention.

What I claim is:

1. In a device of the class described, a writing element having a reduced upper end portion, a resilient clamping element having a straight portion positioned upon said reduced end portion with its adjacent end anchored to said writing

5 element, said clamping element having an upwardly sloping portion extending from said straight portion and terminating in a portion having a hooked end, said sloping portion normally tending to move said clamping element away from said writing element, a slidable ring upon said reduced portion extending over said straight portion and movable against said sloping portion for forcing said hooked end against said writing element.

2. In a device of the class described, a writing element, a resilient clamping member having one end anchored to the upper end of said writing element, said member having a short portion at its upper end terminating in a sloping portion, said sloping portion terminating in an elongated portion having a hooked end and a ring on said element encircling a short portion of said member and movable against said sloping portion for forcing said hooked end against said writing element.
